UNITED STATES PATENT OFFICE.

EDWARD J. MARES, OF WILBER, NEBRASKA.

TOOL FOR REMOVING POPPET VALVES.

Application filed August 27, 1921. Serial No. 495,863.

To all whom it may concern:

Be it known that I, EDWARD J. MARES, a citizen of the United States, residing at Wilber, in the county of Saline and State 5 of Nebraska, have invented a new and useful Tool for Removing Poppet Valves, of which the following is a specification.

This invention relates to tools for removing poppet valves.

10 The object is to provide a tool for use in releasing the pressure of the coiled springs surrounding the stems of poppet valves in internal combustion engines, in order to permit of the removal of the key or pin forming an abutment for one end of such springs, so that the said valve and stem may be withdrawn from the valve cage and the seat therein as well as the valve reground.

Another object is to provide a simple tool 20 in the form of pliers having jaws sufficiently wide apart to receive therebetween the lower or valve-seat end of the valve cage of an engine and the spring-engaging washer at the other end thereof, in such manner as 25 to compress the spring when the handles of the pliers are forced together, thus providing ample room for the operator to remove the transverse pin in the valve stem, the device being of simple construction and capable 30 of manufacture at a low cost and readily applied and operated by any unskilled person.

A full and complete understanding of the invention may be obtained from a consideration 35 of the following detailed description, taken in connection with the accompanying drawing forming a part of this specification; it being understood that while the drawing shows a practical form of the invention, the latter is not confined to strict 40 conformity therewith, but may be changed or modified, so long as such changes or modifications mark no material departure from the salient features of the invention, 45 as specifically pointed out in the appended claim.

In the drawing, in which similar reference characters designate corresponding parts throughout the several figures:—

50 Fig. 1 is a side elevation of the tool applied to the valve cage and valve of an automobile engine, the valve spring being compressed and the key or pin free to be driven out of the stem;

55 Fig. 2 is a plan view of the same;

Fig. 3 is a detail sectional view taken

transversely through the lower jaw of the tool and showing the manner of supporting the lower end of the valve-cage and the valve thereon.

The device of the present invention is especially designed for use in connection with the valves and valve cages of the Buick automobiles, and has been illustrated in connection with such but, the same may be 60 used in removing the springs of valves of other makes with equal facility. More or less difficulty has been encountered in handling these parts of this particular car, for the reason that the valve cage must be removed from the engine casing or block when it is desired to remove therefrom the valve proper for the purpose of grinding the same and the valve seat, which latter is carried 65 at the lower end of said cage. The distance between the lower end of the stem carrying the valve having its seat in the lower end of the cage, and the upper end of the spring mounted on top of the cage in surrounding 70 relation to the valve stem, is relatively great 75 and prohibits the use of an ordinary tool of this character, as the compression must be applied at these two distant points. The present device is designed for this purpose.

In the drawing there is shown a valve 85 cage 1, in the form of a cylinder formed of appropriate metal, having at its lower end an internal valve seat 2, and its upper end closed as at 3 and provided with an upstanding, tubular extension 4, the said valve cage 90 being adapted to be seated in a socket provided in the engine block in proper position over the cylinder, and adapted to be held therein by a threaded nut entering the upper end of the socket and bearing against 95 the top of the cage, in the usual manner, illustration of the latter elements being, however, deemed unnecessary.

A valve disk 5 having the usual tapered peripheral edge, is seated in the seat at the 100 lower end of the cage, and said valve is provided with a central, upstanding stem 6 secured thereto and passing upwardly through the tubular extension 4 and terminating at a distance above the same, the said 105 stem having a transverse passageway located adjacent to its upper end for the reception of a pin or key 7 projecting out from either side of the same.

A washer 8 is mounted on the valve stem 110 immediately below the transverse pin or key, and a coiled expansion spring 9, sur-

rounding the tubular extension 4 of the valve cage and the projecting upper end of the stem 6, is interposed between the lower face of the washer 8 and the closed upper end of the valve cage 3, said spring being adapted, when expanded, to normally hold the valve proper in its seat at the lower end of the cage, in a well known manner.

As thus far described, the elements are those found in the construction of a valve and cage used in the above-mentioned make of automobile and form no part of the present invention, the object being to provide a tool which may be used to form a support for the valve 5 and the cylindrical cage 1 resting thereupon, while the washer 8 may be forced downwardly and away from its abutment against the underside of the transverse pin 7, thus compressing the spring 9, in order to remove the said pin or key 7 from its seat in the valve stem.

To this end, the device comprises a pair of jaws 10 and 11, respectively, the jaws 10 being of angular formation, as viewed from the side, and the jaw 11 being preferably substantially straight, as shown in Fig. 1 of the drawing. The angular jaw 10 is adapted to support the lower end of the cage 1 together with the valve stem, and is provided with a transversely disposed, somewhat elongated base 12, formed integrally therewith, and provided with a concave seat 13, conforming to and adapted to receive the lower convex face of the aforesaid valve disk 5, and to support the same, together with the cage 1 and other parts carried thereby.

The base 12 is joined to a horizontal arm 14 arranged centrally thereof, which latter is directed upwardly as at 15, and is there somewhat widened for the reception of a transverse bolt 16, and thence angularly bent to extend to the rear in the form of a handle 17.

The other jaw 11 comprises a substantially straight bar having a relatively thin active end, as indicated at 18, the latter being bifurcated to provide spaced arms 19, having their free ends rounded on their top edges to provide noses 20 for the purpose of being wedged beneath the projecting ends of the pin or key 7, and resting upon the upper face of the washer 8.

The upper jaw 11 is extended to the rear, having an intermediate reduced and flattened portion where crossing the upper angular bend of the other jaw, and provided with a suitable aperture for the re-

ception of the aforesaid pivotal bolt 16, upon which the same is fulcrumed, the said extension of the upper jaw terminating in a handle 21 of equal length with the handle 17, and adapted to coact therewith, and having the reduced and flattened portion 22 formed in the side thereof adjacent to the handle 17, so that the outer faces of the two handles are flush with the side edges of the upper jaw 11.

When the base 12 and the bifurcated end of the upper jaw are applied to the valve and cage as described and shown in Fig. 1, it will be observed that the handles are somewhat spaced apart at their free ends, so that a further pressure upon the same may be exerted if desired, by the hand of the operator and the same supported thereby, while the other hand may be employed in extracting the pin or key 7 from its seat in the upper end of the valve stem, after which the said valve may be properly ground as well as the seat at the lower end of the valve cage 1.

From the foregoing, it will be seen that a simple and efficient device has been provided for removing the pin or keys from valve stems of engines, the same being capable of being handled by one hand of the operator, leaving the other hand free to drive out the key, and that the same may be manufactured and sold at a low cost.

What is claimed is:—

A device of the character described comprising spaced jaws, one of said jaws having a straight, rearwardly-directed extension carrying a pivotal bolt and terminating beyond the bolt in an operating handle, the other jaw having a rearward extension angularly-bent towards the extension of the first jaw, and crossing the same, and pivotally mounted on the bolt and terminating in a second operating handle, the first-named jaw having its active end relatively thin and bifurcated to provide two horizontally spaced arms for straddling a valve stem to compress the valve spring and washer, the second-named jaw having a base plate provided with a seat for the reception of the lower end of the valve and the cage therefor, and adapted to coact with the first jaw in compressing the spring to free the pin or key of the valve stem, when the coacting handles are forced together.

In testimony, that I claim the foregoing as my own, I have hereto affixed my signature.

EDWARD J. MARES.
